Des. 177,536
Patented Apr. 24, 1956

177,536

ELECTRIC FOOD SLICING MACHINE

Harry Preble, Jr., Cross River, and Jack Gilbert, Newburgh, N. Y., assignors to General Slicing Machine Co., Inc., Walden, N. Y., a corporation of New York

Application April 29, 1955, Serial No. 35,755

Term of patent 14 years

(Cl. D55—1)

Fig. 1 is a perspective view of an electric food slicing machine, showing our new design as viewed from the front and one side thereof; and

Fig. 2 is a perspective view of said machine as seen from the rear and the other side thereof.

We claim:

The ornamental design for an electric food slicing machine, substantially as shown.
